PREFABRICATED BUILDING UNIT FOR STORAGE

Tadashi Hanaoka, Kawasaki, Isao Kaneko, Tokyo, and
Iwao Shiina, Yamato, Japan, assignors to Misawa
Homes Co., Ltd., Tokyo, Japan

Filed Nov. 6, 1972, Ser. No. 303,808

Claims priority, application Japan Sept. 19, 1972

Term of patent 14 years

Int. Cl. D25—02

U.S. Cl. D13—1 R

FIG. 1

FIG. 3

FIG. 2

VI

FIG. 4

FIG. 6

FIG. 5

FIG. 7

FIG. 1 is a top plan view of a prefabricated building unit for storage showing our new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a cross sectional view on line VI—VI of FIG. 2, showing the wall to which the unit is mounted in dashed lines, and

FIG. 7 is a perspective view of the subject building unit showing the doors opened.

The elements shown in dashed lines in the Figures are for illustrative purposes.

We claim:

The ornamental design for a prefabricated building unit for storage, as shown and described.
